UNITED STATES PATENT OFFICE.

FREDERICK LOEDIGE, OF CHICAGO, ILLINOIS.

VALVE-PACKING.

No. 887,405.

Specification of Letters Patent. Patented May 12, 1908.

Application filed February 25, 1908. Serial No. 417,686.

To all whom it may concern:

Be it known that I, FREDERICK LOEDIGE, a citizen of the United States, residing at 93 Orchard street, Chicago, in the county of 5 Cook and State of Illinois, have invented a new and useful Improvement in Valve-Pack-
ing, of which the following is a specification.

My invention relates to an improved construction of metal packing for the piston of a 10 valve, which shall render it durably effective in preventing leakage past the piston of the fluid-pressure controlled by the valve.

While my improvement is adaptable to the pistons of valves of various kinds for differ- 15 ent purposes, I have more especially devised it for use on a locomotive-engine throttle-
valve and therefore, though without intend-
ing to limit it thereto, describe it in that par- 20 ticular connection, in which it is illustrated in
the accompanying drawing, showing, by a
broken view, a longitudinal section of the de-
vice.

In the rear head 1 of a boiler 2 is seated, 25 at an opening 3, a metal stuffing-box 4 pro-
jecting into the boiler and flanged at 5 on its
outer edge. The valve-stem 6 extends cen-
trally through the stuffing-box in which is 30 confined about it a sleeve 7 of brass or other
metal relatively harder than the metal of
which the packing 8, hereinafter described, is 35 composed. The outer end of the bushing 7
is formed into an inwardly tapering packing
seat 9. The packing 8 is an annular head of
general cone-frustum shape with its tapered
section tapering to an angle more acute than 40 that of the seat 9, to bear at its inner end
against the latter at a considerable depth
therein, substantially as represented, while
toward the outer end of the packing-head its
tapering section finds bearing about the outer 45 edge of the mouth of the stuffing-box, thus
having two bearing-points at and from which
to exert its packing function. The interior
of the packing is chambered out, as shown at
10, to reduce the friction against the valve- 50 stem, as one purpose, and for the further pur-
pose of weakening it about its inner and outer
ends so that, being formed of metal rela-
tively softer than that of the bushing, it will
yield under the force of the fluid-pressure 55 against the inner end of the bushing, to hug
closely about the valve-stem at the opposite
ends of the chamber 10. The metal I prefer
to use for the packing-head, which describes
a circle of uniform diameter about its outer- 60 end portion, is a composition consisting of tin

and Babbitt metal, in the proportions of about three parts of each to two parts of lead. A metal washer 11, preferably of brass and shown to be concave on its inner face, sur- 60 rounds the stem and is confined at its con-
cave face against the outer end of the pack-
ing-head by the gland 12, which is secured in
place by the nuts 13 on the threaded ends of
the studs 14 extending from the head 1 65 through the flange on the stuffing-box and
a flange 15 on gland.

Fluid-pressure in the boiler exerted against the bushing 7 forces its seat against the seat-
ing-end of the head 8, thereby compressing 70 the weakened inner end of the latter about
the valve-stem to prevent leakage at that
point, while the pressure, acting in opposi-
tion to the confinement by the gland of the 75 packing-head against the mouth of the stuff-
ing-box, beddingly compresses the softer
metal of the head against the same and thus
prevents leakage of pressure about the bush-
ing at that point.

What I claim as new and desire to secure 80 by Letters Patent is—

1. In combination with a valve-stem, a springless packing therefor comprising a stuffing-box through which the stem passes, containing a metal bushing having an in- 85 wardly-tapering packing-seat in its outer end, and an annular metal tapering packing-
head confined about the stem to bear at its narrower inner end against said seat and to-
ward its outer end against the mouth of the 90 stuffing-box.

2. In combination with a valve-stem, a stuffing-box through which the stem passes, containing a metal bushing having an in- 95 wardly-tapering packing-seat in its outer end, and an annular tapering packing-head of metal relatively softer than that of said bushing, confined about the stem to bear at its narrower inner end against said seat and toward its outer end against the mouth of 100 the stuffing-box.

3. In combination with a valve-stem, a stuffing-box through which the stem passes, containing a metal bushing having an in- 105 wardly-tapering packing-seat in its outer end, and an annular tapering chambered packing-head of metal relatively softer than that of said bushing confined about the stem to bear at its narrower inner end against said seat and toward its outer end against the 110 mouth of the stuffing-box.

4. In combination with the rear head of a

boiler, a throttle-valve stem working through the said head and a stuffing-box extending through said head and through which said stem passes, a metal bushing in the stuffing-box having an inwardly-tapering packing-seat in its outer end, an annular chambered tapering packing-head of metal relatively softer than that of said bushing, bearing at its narrower inner end against said seat and

toward its outer end against the mouth of 10 the stuffing-box, a washer on the outer end of said packing-head, and a gland secured on said head to bear against the washer.

FREDERICK LOEDIGE.
